MASONRY WALL CONSTRUCTION

Johannes T. Sentrop, Wyoming Township, Kent
County, Mich.

Application October 28, 1937, Serial No. 171,462

6 Claims. (Cl. 72—41)

The present invention relates to building construction, particularly masonry walls and other parts combined herewith in building construction; and its object is, generally, to provide improved construction of this character; and particularly, to provide wall members, as building blocks and the like, so formed as to be combined with other wall members, as bricks of usual size and shape, to form an improved masonry wall. 5 all said members being securely and compactly bonded together by mortar or cement; and further, to provide such block members whose mutually adjacent surfaces are so formed as to be thus bonded together; and further, to provide such block members and horizontal beams or floor joists so formed as to be thus securely held together; and further, to provide improved means and methods for supporting lathing on such walls spaced therefrom to provide air spaces between 10 the wall and the lathing and the plastering carried thereby. These and any other objects hereinafter appearing are attained by, and the invention is embodied in, and carried out by, the illustrative structures particularly described in the 15 body of this specification and illustrated by the accompanying drawing in which:

Figure 1 is an inner side view in perspective of building construction including a masonry wall, lathing and plastering carried thereby and 20 horizontal beams or floor joists supported at their ends by the wall, together with a filling between the upper ends of the beams;

Figure 2 is a view in perspective of one of the building block members of the wall;

Figure 3 is a top plan view of one of said block members and a portion of another with mortar between bonding them together;

Figure 4 is a top plan view of part of the wall adjacent a door opening therethrough, with lathing and plastering, and the door jamb shown in horizontal section;

Figure 5 is a top plan view of part of the wall adjacent a window opening therethrough and of a horizontal beam supported at its end on the 45 wall, the frame of the window being shown in horizontal section;

Figure 6 is a top plan view of a corner portion of the wall.

The masonry wall illustrated by the drawing 50 comprises a suitable foundation 1 and superposed horizontal courses of wall members, the blocks 3, 3¹ forming the inner side of the wall and bricks 4, 4¹ forming the outer side of the wall, all these members being compactly bonded together by mortar indicated at 5. As indicated

in Figure 1, the lower portion of the wall above the foundation 1 and formed of two courses of blocks 3, 3¹ and six courses of bricks 4, 4¹ is thicker than the wall's upper portion which is formed of one course of blocks 3 and three courses of bricks 4, 4¹, a water-table 6 and a course of bricks 4 being shown between said upper and lower wall portions.

The building blocks of molded concrete and the like may be of any suitable rectangular shape such as that illustrated, the blocks 3 having cavities 7 opening downwardly and inwardly of the wall. Horizontally extending rabbets 8 form internal instead of external corners at the outer and upper or outer and lower sides (preferably at the upper sides as shown) of these blocks, which rabbets are of sufficient horizontal depth to receive the inner end portions 9 of a course of bricks 4 which are laid with their ends inwardly and outwardly, and so that the outer surfaces of the bricks 4, 4¹ of the wall may lie in the same vertical plane. Thus the rabbets have a horizontal depth of approximately four inches and a vertical depth of approximately two inches to receive the inner end portions, i. e. the inner 20 half 9 of bricks 4 of usual dimensions, 2 by 4 by 8 inches. It will be seen that these bricks 4 thus placed serve to securely bind the brick outer side of the wall and the wall's building block inner side securely together. The other bricks 4¹ between the courses composed of the bricks 4 may be laid in any desired combinations, such, for instance, as are indicated in the drawing. As shown in Figures 2, 3, 4 and 5 the ends of the blocks desirably have vertical recesses or depressions 10 deeper at the top of the block than at its bottom, with vertical grooves 11, so that when the mortar indicated at 5¹ is applied between the adjacent ends of a pair of these blocks it runs into said grooves and holds the blocks against 25 relative inward and outward displacement. In spaces between the blocks filled with the mortar, horizontally disposed rods 12 are shown having upwardly turned hook ends 13 these rods projecting inwardly from the blocks, and horizontally disposed rods 14 may be laid on these rods 12 and retained in spaced relation with the blocks' inner sides by suitable means as the hook ends of the rods 12, whereupon suitable lathing 14 may be secured on these rods by means of any 30 suitable tie members as the wires 15. Plastering 16 applied to this lathing forms an air space between the blocks and the plastering. Jambs 20 having members 17, 18, 19 for the closure 20 of a door opening 21 through the wall may be 35

- held in place by suitable bolts 22 as shown in Figure 4; and frames 23 for the sash 24 of window openings 25 through the wall may be incorporated as seen in Figure 5, mortar being applied between the blocks and said jambs or frames as indicated in these views. Dovetail mortises 26 are formed in the inner sides of the blocks of a course thereof, as the blocks 31 of the lowest course, half of each mortise being 5 formed by the surface 27 of each of a pair of adjacent blocks, said surfaces being inclined toward each other and toward the inner side of the wall as shown in Figure 5. Horizontal beams 28 have at their ends dovetail tenons 29 adapted 10 to fit in these mortices. These beams are desirably molded concrete with reinforcements 30 and have a desired cross sectional shape similar to that shown in Figure 1, with edge portions 31 inclined downwardly and toward such edge portion 15 of the adjacent beam. A form board 32 may be supported as by wires 33 from floor joists 34 laid on the beams whereupon a concrete filling 35 having reinforcements 36 may be applied on the board 32 and between the edge portions 31 to 20 form a continuous flat floor surface.
- In Figure 6 is shown in top plan view a corner portion of the wall composed of plain blocks 32 with a bent connecting rod 37 and laid in break-joint relation.
- 30 It will be seen that the masonry courses consisting of a course of building blocks of the form shown and a plurality of courses of bricks, all compactly bonded together as illustrated in Figure 1, provides a masonry wall wherein an outer 35 "veneer" of bricks having a plane outer surface is in a peculiarly stable manner united with the said blocks to form a masonry wall construction; that the rods 12 being driven to a predetermined depth into the mortar 51 before it hardens serves 40 to position the lathing and plastering at the desired distance from the wall; that the mortar 52 or 53 between the inclined ends 271 of the blocks and the door or window casings serves to hold such casings securely in position; and that 45 the mortar bonding the courses of bricks and concrete blocks together, with the inner end portions of the bricks in the rabbets, provides very effective water-proof joints between all the wall members.
- 50 The invention being intended to be pointed out in the claims, is not to be limited to or by details of construction and arrangement of the particular embodiment thereof illustrated by the drawing or hereinbefore described.
- 55 I claim:
1. In a masonry wall, a compactly bonded flat top and flat bottom course comprising wall members adjacent one side of the wall having rabbeted inner corners and wall members laid in a plurality of courses adjacent the other side of the wall with the inner end portions of the members of one of said plurality of courses compactly bonded in said rabbeted corners, and rods 50 bonded between the rabbeted members projecting therefrom and lathing carried by said rods and spaced from the wall to provide an air space between the wall and the lathing.

bonded at all their surfaces in said rabbeted corners.

2. In a masonry wall, a compactly bonded course comprising approximately rectangular building blocks forming one side of the wall having rabbeted inner corners, and bricks laid in a plurality of courses forming the other side of the wall with the inner end portions of the bricks of one of said plurality of courses compactly bonded at all their surfaces in said rabbeted corners.

3. In a masonry wall, a compactly bonded course comprising approximately rectangular building blocks forming one side of the wall having rabbeted inner corners, and bricks laid in a plurality of courses forming the other side of the wall with the inner end portions of the bricks of one of said plurality of courses compactly bonded at all their surfaces in said rabbeted corners and with the outer surfaces of the bricks of said plurality of courses lying in the same vertical 20 plane.

4. In a masonry wall, a compactly bonded flat top and flat bottom course comprising wall members adjacent one side of the wall having rabbeted inner corners and wall members laid in a plurality of courses adjacent the other side of the wall with the inner end portions of the members of one of said plurality of courses compactly bonded in said rabbeted corners, and another course comprising approximately rectangular building blocks having dovetail mortises in their sides, and horizontal beams having dovetail tenons fitting in the mortises.

5. In a masonry wall, a compactly bonded flat top and flat bottom course comprising wall members adjacent one side of the wall having rabbeted inner corners and wall members laid in a plurality of courses adjacent the other side of the wall with the inner end portions of the members of one of said plurality of courses compactly bonded in said rabbeted corners, and another course comprising approximately rectangular building blocks having dovetail mortises in their sides, and horizontal beams having dovetail tenons fitting in the mortises, adjacent pairs of the 45 beams having downwardly extending mutually approaching edges with concrete filling between said edges.

6. In a masonry wall, a compactly bonded flat top and flat bottom course comprising wall members adjacent one side of the wall having rabbeted inner corners and wall members laid in a plurality of courses adjacent the other side of the wall with the inner end portions of the members of one of said plurality of courses compactly bonded in said rabbeted corners, and rods 55 bonded between the rabbeted members projecting therefrom and lathing carried by said rods and spaced from the wall to provide an air space between the wall and the lathing.

JOHANNES T. SENTROP.
